UNITED STATES PATENT OFFICE.

JAMES EDWARDS, OF PHILADELPHIA, PENNSYLVANIA.

METHOD OF AND LAST FOR MAKING TURNED SHOES.

Application filed September 23, 1925. Serial No. 58,052.

My invention relates to the manufacture of turned shoes, and more particularly to a method of securing the sole to the upper, and to means for carrying the method into effect.

Turned shoes differ from welt and other types, in that they are lighter and more flexible because they have but a single thin layer of sole stitched directly to the upper.

10 In making turned shoes, the usual plan has been to make the lining of the upper larger than the outside material in order that when turned, the outside material will be free of wrinkles. The lining, being larger than the outside material, does not fit when the shoe is turned right side out and, unless the slack is taken up, the lining wrinkles and causes serious discomfort to the wearer. The usual method of taking up the slack in the lining 20 is to fold it into a single plait at the rear seam of the shoe. This plait is always objectionable and, unless the workman performs the folding operation with great skill and care, the lining does not fit smoothly and the shoe is defective.

The objects of my invention are to provide a method of making turned shoes whereby the plait at the rear of the shoe is dispensed with and the lining made to fit smoothly, and to provide means for carrying the method into effect.

These objects, and other advantageous ends which will be described hereinafter, I attain in the following manner, reference being had to the accompanying drawings in which—

Figure 1 is a side elevation of a last constructed in accordance with my invention, showing it in inverted position as applied to a standard,

40 Figure 2 a rear end view of the last,
Figure 3 a plan view of the last,

Figure 4 a bottom plan view of an upper made in accordance with my invention showing it inside out,

45 Figure 5 a like view showing the upper right side out,

Figure 6 a plan view of the upper shown in Figure 4, illustrating its front part as temporarily fastened to a sole and the last,

50 Figure 7 a section on line 7—7 of Figure 6,

Figure 8 a fragmentary section through the rear part of a shoe made in accordance with my invention, and

55 Figure 9 a like view of the rear part of a shoe made according to the old method.

For convenience, the term "upper" will be

used as including both vamp and quarter and both outer material and lining, and the term "leather" will be used as designating the outside material whether that material be of leather or fabric.

In carrying my invention into effect, the lining is made to smoothly and accurately fit the leather. This would cause the leather to wrinkle when the upper is turned inside out for lasting and the lasting could not be properly effected unless means were provided for taking up the slack in the leather and releasing that slack when the parts are again reversed. To accomplish this, I use a primary last which conforms in shape and dimensions with the standard last for the required size of shoe except that the heel is shorter and is provided with a vertical groove of sufficient depth to receive the slack in the leather. 70 The sole is then secured to the last in the usual manner but with its heel projecting loosely and somewhat beyond the heel of the last. The upper is then smoothly but temporarily secured to the sole and last in the 75 usual manner but with the slack in the leather disposed in the groove. The stitching is then performed in the usual way, the temporary fastenings removed, the last removed, the partially made shoe turned right 80 side out, then placed upon a standard last and finished in the usual manner. This last takes up the slack which was gathered in the groove of the primary last and a shoe is produced with a perfectly fitting lining and 85 which is free from any projection due to 90 taking up slack.

In the drawings, 1 indicates a last, herein-after called the primary last, having the usual socket 2 adapted to fit a standard 3 to 95 hold the last in position when fitting the upper thereon. This last is of standard shape and dimensions for the required size of shoe except that its heel is shorter and is provided with a groove 4, preferably vertical and midway transversely of the heel. A lining 5 is made to smoothly and accurately fit the leather 6 when the upper is right side out. The lining being slightly smaller than the leather, turning the upper inside out will cause the leather to wrinkle but with a primary last so constructed, the lasting may be so effected as to leave both the lining and the leather perfectly smooth except for a fold in the leather taking into groove 4. For the 100 primary lasting the sole 7 is temporarily secured to the primary last by tacks but with 105

2
its heel loosely extending somewhat beyond the heel of the last. The reversed upper is then temporarily secured to the sole and the last by tacks, as shown in Figure 6, and the 5 stitching performed in the usual way. The tacks are then withdrawn, the last removed, the partly constructed shoe turned right side out and placed upon a standard last which will take up the slack in the leather. The 10 shoe is then finished in the usual manner.

The primary last should be of a length sufficient to insure that the lining when lasted thereon, will be of the precise dimensions required for the finished shoe. I find 15 that this result may be attained by making the primary lasts approximately one and a fourth sizes shorter than the standard last. The groove in the heel should be sufficiently large to freely take in whatever slack there 20 may be in the leather.

In Figure 9, I have shown a section of the heel of a turned shoe, made in accordance with the hitherto approved practice, in which is indicated the plait into which the 25 slack of the lining is folded.

My invention dispenses with the necessity of careful folding, or of any folding of a plait to take up slack, dispenses with the usual projection in the inner heel of the 30 shoe (as shown in Figure 8), due to the plait, and produces a shoe with smooth lining and smooth leather.

While I have described my invention as taking a particular form, it will be understood 35 that the various parts may be changed without departing from the spirit thereof, and hence I do not limit myself to the precise construction set forth, but consider that I am at liberty to make such changes and 40 alterations as fairly come within the scope of the appended claims.

Having thus described my invention, what I claim as new and desire to secure by Letters Patent is:—

45 1. A method of making turned shoes consisting in making an upper with a lining fitting the leather; reversing the upper; temporarily securing a sole and the reversed

upper to a last having space in its heel to receive the slack in the leather; stitching the 50 upper to the sole; removing the last, and finishing the shoe on a standard last.

2. A method of making turned shoes consisting in making an upper with a lining 55 fitting the leather; reversing the upper; temporarily securing a sole and the reversed upper to a last of the proper standard size and form but shorter at the heel than the standard last and having a grooved heel; gathering the slack in the leather into the 60 groove in the heel; stitching the upper to the sole; removing the last, and finishing the shoe on a standard last.

3. A method of making turned shoes consisting in making an upper with a lining 65 fitting the leather; reversing the upper; temporarily securing a sole and the reversed upper to a last of the proper standard size and form but shorter at the heel than the standard last and having a grooved heel 70 with the sole extending loosely beyond the heel of the last; gathering the slack in the upper into the groove in the heel; stitching the upper to the sole; removing the last, and finishing the shoe on a standard last. 75

4. A primary last for turned shoes, having, except as to its heel, the form and dimensions of the standard last but having its heel shorter than that of the standard last to provide space for taking up slack. 80

5. A primary last for turned shoes, having, except as to its heel, the form and dimensions of the standard last but having its heel shorter than that of the standard last and provided with a groove adapted to 85 receive slack.

6. A primary last for turned shoes, having, except as to its heel, the form and dimensions of the standard last but having its heel shorter than that of the standard last and provided with a central vertical groove 90 adapted to receive slack.

In testimony whereof I have signed my name to this specification.

JAMES EDWARDS.
